J. OROSZ

VENTED BARREL BUNG

Filed Nov. 23, 1922

FIG. 1.

FIG. 2.

FIG. 3.

Inventor
J. Orosz

By J. K. Bryant.

Attorney

UNITED STATES PATENT OFFICE.

JOSEPH OROSZ, OF CLEVELAND, OHIO.

VENTED BARREL BUNG.

Application filed November 23, 1922. Serial No. 692,342.

To all whom it may concern:

Be it known that I, JOSEPH OROSZ, a citizen of Hungary, residing at Cleveland, in the county of Cuyahoga and State of Ohio, have invented certain new and useful Improvements in Vented Barrel Bungs, of which the following is a specification.

This invention relates to certain new and useful improvements in vented barrel bungs, and has particular reference to a bung so constructed to permit gas under pressure caused by fermentation of liquid within a barrel, or other reason, escaping through the vented bung and preventing the ingress of air to the barrel.

The primary object of the invention resides in the provision of a vented barrel bung wherein an outwardly opening tensioned valve closes a passage provided in the bung and being operable to permit the gas pressure formed in the barrel to escape through the bung passage against the tension of the spring valve.

A further object of the invention is to provide a vented barrel bung wherein a tensioned valve associated with an air passage in the bung is normally closed and is adapted for automatic operation to permit the escape of gases through the bung passage, and further being capable of manual operation for drawing liquid from a barrel through an independent faucet or a flexible tube associated with the bung.

This application is filed as a continuation, in so far as shown and described in application Serial No. 554,615, filed April 18, 1922, and embodies improvements in the art thereover.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a vented barrel bung constructed in accordance with the present invention, a side wall of the barrel being illustrated in section by dotted lines, a hammer setting frame also being shown by dotted lines for properly positioning the bung within a barrel opening,

Figure 2 is a vertical sectional view taken on line II—II of Fig. 1 showing the air passage in the body of the bung normally closed by the tensioned valve with the lever 60 for manually shifting the valve.

Figure 3 is a top plan view of a modified form of the invention, and

Figure 4 is a cross sectional view taken on line IV—IV of Fig. 3 showing a variably tensioned closure valve for the air passage in the bung and the flexible draw or tube carried thereby.

Referring more in detail to the accompanying drawing, and particularly to Figs. 1 and 2 there is illustrated a tapering barrel bung 1 formed of any desired material, having an axially positioned air vent passage 2 and a laterally positioned longitudinally extending opening 3 adjacent one edge of the bung. The upper end of the air passage 2 is enlarged as at 2^a to form a valve seat 4 intermediate the upper and lower ends of the passage 2 with which a disk valve 5 engages.

The valve 5 carries a perpendicularly extending stem 6 projecting upwardly through the enlarged upper end 2^a of the air passage while a housing embodying an inverted cup-shaped casing 7 having a base flange 8 is secured as at 9 to the outer end of the bung body 1 with the casing 7 disposed outwardly of the air passage 2 as clearly shown in Fig. 2. An opening 10 is formed centrally of the upper wall of the casing 7 and the outer end of the valve stem 6 extends therethrough. A lug 11 is struck-up from the upper wall of the casing 7 and provides an opening 12 at the inner end thereof, a lever 13 being pivotally mounted as at 14 upon the lug 11 with one end thereof pivotally connected as at 15 to the adjacent end of the valve stem 6. A coil spring 16 surrounds the valve stem 6 between the disk valve 5 and the top wall of the casing 7 normally urging the valve 5 in a direction toward the seat 4.

A flexible tube 17 is positioned in the opening 3 of the bung body 1 and is normally closed at its outer end by a stopper 18, the tube 17 being employed for drawing liquid from the barrel through the bung 1 and may be used in lieu of the usual faucet that is independent of the bung.

From the above detail description of the device as illustrated in Figs. 1 and 2, it is believed that the construction and operation thereof will at once be apparent, the liquid,

contents of a barrel being sealed to the atmosphere by the tensioned valve 5 and the stopper 18 in the flexible tube 17. In the fermentation of certain liquids, gases 5 forming in the barrel will be permitted to escape through the air passage 2 by overcoming the pressure of the spring 16 to unseat the valve 5 and automatically escape through the vented bung, the valve being 10 returned to its seat by the spring 16 to prevent air entering the barrel. In drawing off the liquid through the flexible tube 17, the valve 5 may be unseated by pressing on the outer end of the lever 13 to shift the valve 15 against the tension of the spring 16 for equalizing pressure within and outside the barrel and thereby permitting a free flow of liquid through the draw-off tube 17. The U-shaped frame 19 illustrated by dotted 20 lines in Fig. 1 is employed for mounting the bung in the side wall 20 of the barrel by striking the frame 19 with a suitable implement for properly wedging the tapering bung in position. The vented barrel bung 25 is entirely automatic in its operation to permit the escape of gases through the passage 2, the spring 16 effectively retaining the valve 5 upon its seat 4 to exclude the ingress of air to the barrel.

30 In the form of the invention shown in Figs. 3 and 4, the tapering bung body 1^a is provided with an axially positioned air passage 2^b, a lateral longitudinally extending opening 3^a receiving the flexible tube 17^a. 35 An inverted U-shaped strap 7^a is anchored as at 9^a at its ends to the upper side of the bung body 1^a and has a screw plug 21 threaded centrally therethrough and provided upon the lower end thereof with a 40 disk head 22. A valve 5^a of disk formation carries an axially positioned depending pin 23 while a flexible disk washer 24 surrounds the extension pin 23 and engages the bottom face of the valve 5^a, the valve being 45 positioned at the upper end of the air passage 2^b with the pin 23 extending into said passage. A coil spring 16^a is interposed between the valve 5^a and the disk 22 carried by the adjusting screw 21 for normally holding 50 the valve on its seat. The valve 5^a is entirely automatic in its operation, excess gas pressure in a barrel unseating the same against the tension of the spring 16^a to permit escape through the passage 2^b, tension 55 on the spring 16^a being varied by the adjusting screw 21 threaded in the strap 7^a as will be clearly understood from an inspection of Fig. 4.

While there are herein shown and described the preferred embodiments of the

present invention it is nevertheless to be understood that minor changes may be made in the invention without departing from the spirit and scope thereof as claimed.

What is claimed as new is:—

1. In a barrel bung having an air vent passage, an outwardly opening disk valve closing said passage, a frame secured to the outer end of the bung and overlying the passage and valve, and a spring interposed 70 between the frame and outer side of the valve.

2. In a barrel bung having an air vent passage, a disk valve closing said passage, a frame secured to the outer end of the bung 75 and overlying the passage, a spring interposed between the frame and valve, and a flexible tube extending through the bung.

3. In a barrel bung having an air vent passage, a disk valve closing said passage 80 and opening in a direction outwardly of the bung, a frame secured to the outer end of the bung and overlying the passage and valve, and a spring interposed between the frame and outer side of the valve.

4. In a barrel bung having an air vent passage, a disk valve seating therein, a casing carried by the outer end of the bung overlying the passage, a stem carried by the valve and projecting through the casing, and a coil spring surrounding the stem between the valve and casing for holding the valve on its seat.

5. In a barrel bung having an air vent passage, a disk valve seating therein, a casing carried by the outer end of the bung 95 overlying the passage, a stem carried by the valve and projecting through the casing, a coil spring surrounding the stem between the valve and casing for holding the valve on its seat, and a manually operable lever connected to the outer end of the stem for removing the valve from its seat.

6. In a barrel bung having an air vent passage, a disk valve seating therein, a casing carried by the outer end of the bung 105 overlying the passage, a stem carried by the valve and projecting through the casing, a coil spring surrounding the stem between the valve and casing for holding the valve on its seat, and a manually operable lever pivoted to the outer side of the casing and connected to the stem for removing the valve from its seat.

In testimony whereof I affix my signature.

JOSEPH OROSZ.
